DESIGN FOR A BOTTLE

William Richard Kohl, New York, N. Y., assignor to Carr-Lowrey Glass Company, Baltimore, Md.

Application January 6, 1939, Serial No. 82,203

Term of patent 14 years

To all whom it may concern:

Be it known that I, William Richard Kohl, a citizen of the United States, residing at New York, in the county of New York and State of New York, have invented a new, original, and ornamental Design for a Bottle, of which the following is a specification, reference being had to the accompanying drawing, forming part thereof.

I claim:

The ornamental design for a bottle, as shown.

WILLIAM RICHARD KOHL.
